(57) **CLAIM**

The ornamental design for a bottle opener, as shown and described.

DESCRIPTION

FIG. 1 is a bottom perspective view of a bottle opener;

FIG. 2 is a alternate perspective view thereof;

FIG. 3 is a slightly angled perspective view thereof;

FIG. 4 is a bottom plan view thereof;

FIG. 5 is a front elevational view thereof; and,

FIG. 6 is a cross-sectional view thereof, taken on line 6-6 of FIG. 5.

The broken line showing of a bottle is for the purpose of illustrating environmental structure and forms no part of the claimed design.
